CLAIM

We claim the ornamental design for a table top, as shown and described.

DESCRIPTION

FIG. 1 is a perspective view of a table top, showing our new design;

FIG. 2 is a top plan view of the table top shown in FIG. 1; FIG. 3 is a bottom plan view of the table top shown in FIG. 1;

FIG. 4 is a front view of the table top shown in FIG. 1; FIG. 5 is a rear view of the table top shown in FIG. 1; FIG. 6 is a left side view of the table top shown in FIG. 1; FIG. 7 is a right side view of the table top shown in FIG. 1; and,

FIG. 8 is a perspective view of the table top shown in FIG. 1, shown in an alternate environment.

The broken lines depict portions of the table top that form no part of the claimed design.

1 Claim, 8 Drawing Sheets
